Patented Aug. 8, 1972

224,608

MIRRORED COSMETIC CONTAINER

Hideno N. Okuhara and Hiroko L. Okuhara, both of
6449 N. Greenview Ave., Chicago, Ill. 60626

Filed July 26, 1971, Ser. No. 166,326

Term of patent 14 years

Int. Cl. D3—02

U.S. Cl. D86—10

FIG. 1

FIG. 2

FIG. 3

FIG. 4

FIG. 5

FIG. 6

FIG. 1 is a perspective view of a mirrored cosmetic container showing our new design;

FIG. 2 is a rear view thereof;

FIG. 3 is a side view thereof;

FIG. 4 is a front view thereof;

FIG. 5 is a top view thereof;

FIG. 6 is a side view of the design of FIGS. 1-5 with the face of the body disposed parallel to the base thereof.

We claim:

The ornamental design for a mirrored cosmetic container, as shown and described.
